UNITED STATES PATENT OFFICE.

ELI YOUNG, OF EAST AUBURN, CALIFORNIA, ASSIGNOR OF ONE-HALF TO JOSEPH JOHNSON, OF EAST AUBURN, CALIFORNIA.

WIRE-STRETCHER AND BUGGY-JACK.

1,151,323.

Specification of Letters Patent. Patented Aug. 24, 1915.

Application filed August 2, 1912. Serial No. 712,967.

To all whom it may concern:

Be it known that I, ELI YOUNG, a citizen of the United States, residing at East Auburn, in the county of Placer, State of California, have invented certain new and useful Improvements in Wire-Stretchers and Buggy-Jacks; and I do hereby declare the following to be a full, clear, and exact description of the invention, such as will enable others skilled in the art to which it appertains to make and use the same.

This invention relates to a combined wire stretcher and buggy jack.

The principal object of the invention is to provide a device of the character described which may be either employed for stretching fences or for elevating buggies or other vehicles.

Another object of the invention is to provide a main frame having a carriage movable therealong and a novel means for shifting the carriage and for simultaneously locking the same in any adjusted position along the frame.

A further object of the invention is to provide a device of the character described which is composed of a minimum number of parts, is therefore simple in construction and is cheap to manufacture.

With these and other objects in view, the invention consists in the construction and novel combination of parts hereinafter fully described, illustrated in the accompanying drawings and pointed out in the claim hereto appended; it being understood that various changes in the form, proportion, size and minor details of construction within the scope of the claim may be resorted to without departing from the spirit or sacrificing any of the advantages of the invention.

In the drawings: Figure 1 is a side elevation showing the device employed as a wire stretcher, Fig. 2 is a rear elevation thereof showing the device employed as a hoisting jack, Fig. 3 is a side elevation thereof, Fig. 4 is a detail longitudinal sectional view taken on the line 4—4 of Fig. 1, Fig. 5 is a detail sectional view through one of the dogs taken on the line 5—5 of Fig. 1, Fig. 6 is a perspective view of the carriage, the lever and dogs being removed, Fig. 7 is a perspective view of the detachable base, and Fig. 8 is a perspective view of one of the dogs.

Like reference numerals designate corresponding parts in all the figures of the drawings.

Referring to the drawings, the invention comprises a main frame A and a carriage B which is slidably mounted thereon.

The frame consists of a pair of spaced parallel bars 5—5 of angle iron construction, which are connected at one end by a cross bar 6, each angle iron including a base flange 7 and a lateral flange 8, the latter being each formed with a series of teeth 9 which extend in a direction toward the cross bar 6. The cross bar 6 is centrally formed with an outwardly projecting eye 6^a adapted for engagement with a chain 10 when the device is being used as a wire stretcher, as shown in Fig. 1 of the drawings.

The carriage B consists of a pair of spaced transversely disposed sliding elements 11—11 which are each formed from strap metal. Each slide includes a central portion 12 which is disposed between the lateral flanges 8 of the angle bars and portions 13—13 which are formed into bearings 80 for engagement with the base flanges 7 of the bars. The central portions 12 of the elements 11 are connected by a longitudinally disposed support 14 which operates between the lateral flanges 8 of the bar. The 85 end of the support opposite the cross bar 6 projects beyond the respective sliding element 11, and is formed with an eye 15 for engagement with a chain 16 when the device is used as a wire stretcher.

Centrally secured to the support 14 is a pivot pin 17 which projects outwardly in the general direction of the teeth 19. Fulcrumed adjacent one end upon the pin is an operating lever 18, said lever extending 95 across the teeth 9 of the bars 5. Secured to the lever 18 on opposite sides of the pin 17 and in alignment with the teeth 9 of the bars 5 are pivot pins 19—19. Dogs 20—20 are each fulcrumed intermediate its ends upon a 100 pin 19. That end of each dog extending toward the cross bar 6 is formed with a depending tooth 21 adapted for engagement with the teeth 9 of the respective bar 5, and extending downwardly on either side of the 105 tooth 21 are guide fingers 22—22, said fingers being disposed on opposite sides of the lateral flange 8 of the respective bar 5. These fingers serve to retain the tooth 21 in engagement with the teeth 9 during the 110

- movement of the lever 18. The dogs 20 are fulcrumed upon the pins 19 for not only permitting relative lateral movements between the same and the lever, but also for 5 permitting of a slight longitudinal movement thereof. The rear ends of the dogs 20 are undercut, as at 23, and secured to the lever 18 intermediate the dogs 20 is a spring 24. This spring is centrally connected to the 10 lever by any suitable means, and has its free ends extending within the undercut portions 23 of the dogs and bearing against the rear end thereof to cause the teeth 21 to be yieldably held in engagement with the teeth 9. 15 Secured to the end of the support 14 adjacent the cross bar 6 is a laterally extending support 25. This support extends beyond the frame A and serves to support an axle of a vehicle (not shown).
- 20 When the device is employed for raising vehicles, a base 26 is connected to the free ends of the side bars 5 by any suitable means. The frame is then positioned vertically as shown in Figs. 2 and 3 of the drawings.
- 25 In operation, when it is desired to use the device either as a wire stretcher or as a lifting jack, the lever 18 is reciprocated and as a result, the dogs 20 are caused to successively engage the teeth 9 of the parallel 30 bars 5 and thereby shift the carriage B

along the frame A, as will be readily understood.

What is claimed is:

A device of the class described comprising spaced, parallel mutually connected rack bars, a pair of metal straps disposed transversely of one side of the rack bars and each terminating in hooks that slidably engage the corresponding rack bars, a bridge piece connecting the straps intermediate of the 35 rack bars and adapted at one end for attachment of a wire to be stretched, a lever pivoted upon the bridge piece, pawls carried by the lever in position to alternately engage the rack bars respectively upon actuation of 40 the lever, and a spring arranged on said lever to yieldingly retain the pawls in engagement with the racks, each pawl having depending fingers embracing its rack and being pivotally movable with respect to the 45 lever, both in a plane parallel to the plane of movement of the lever and toward and away from the rack.

In testimony whereof, I affix my signature, in presence of two witnesses.

ELI YOUNG.

Witnesses:

JOHN B. LANDIS,
A. E. FALCH.
